(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the notebook computer of FIGS. 1-8 in a first alternate configuration;

FIG. 10 is another perspective view of the notebook computer of FIG. 9 in a first alternate configuration;

FIG. 11 is a perspective view showing the notebook computer of FIG. 9 in a second alternate configuration;

FIG. 12 is another perspective view of the notebook computer of FIG. 9 in a second alternate configuration;

FIG. 13 is a perspective view thereof showing the notebook computer of FIG. 9 in a third alternate configuration;

FIG. 14 is another perspective view of the notebook computer of FIG. 9 in a third alternate configuration;

FIG. 15 is an enlarged view of the portion, labeled '15' in FIG. 9;

FIG. 16 is an enlarged view of the portion, labeled '16' in FIG. 9; and,

FIG. 17 is an enlarged view of the portion, labeled '17' in FIG. 11.

The dashed broken lines shown in the drawings illustrate portions of the notebook computer that form no part of the

(Continued)

claim design. The long-dash short-dash broken lines represent the extents of the detail views and form no part thereof.

1 Claim, 15 Drawing Sheets
